UNITED STATES PATENT OFFICE.

FRANK KARÁCSONYI, OF YONKERS, NEW YORK, ASSIGNOR OF ONE-THIRD TO
GERGELY BLÁGA, OF HASTINGS-UPON-HUDSON, NEW YORK.

SPRING-HEEL FOR SHOES.

1,099,180.

Specification of Letters Patent.

Patented June 9, 1914.

Application filed January 16, 1914. Serial No. 812,452.

To all whom it may concern:

Be it known that I, FRANK KARÁCSONYI, a subject of the King of Hungary, residing at Yonkers, in the county of Westchester and State of New York, have invented certain new and useful Improvements in Spring-Heels for Shoes, of which the following is a specification.

This invention relates to certain new and useful improvements in spring heels for shoes.

An object of the invention aims to relieve the strain and jars on the heel of the foot by providing a spring heel that will absorb such shocks.

A further object of the invention is to provide a spring heel especially adapted for army shoes where the wearer is subjected to excessive walking, the heel being uniformly cushioned to evenly distribute the wear.

With the above and other objects in view which will appear as the nature of the invention is better understood, the same consists in the novel construction, combination and arrangement of parts to be hereinafter more fully described and then claimed, reference being had to the accompanying drawing by like characters throughout the several views and wherein:—

30 Figure 1 is a perspective view of a shoe embodying my invention. Fig. 2 is an enlarged longitudinal sectional view of the heel illustrating the manner of cushioning the same. Fig. 3 is a horizontal sectional view of the heel, and, Fig. 4 is a sectional view of a portion of the heel illustrating a manner of guiding the telescoping sections.

Referring more particularly to the drawing accompanying this application, the reference letter S designates the shoe provided with the heel H. The heel H is provided with an extreme upper and lower leather lift 10 and 11 while the intermediate sections are formed of metallic telescoping members suitably secured to the leather lifts. An inverted cup-shaped member 12 is secured to the upper lift 10 by fastening screws 13 and to be received within the cup-shaped member 12 is the upper telescoping section

50 14 and secured thereto by suitable fastening means as shown at 15. A plate 16 is received within the upper telescoping section 14 and retained therein by the fastening means 17 and depending from said plate 16 are the cylindrical members 18 open at their

lower ends. A transverse pin 19 extends across the lower end of the cylindrical members 18 for purposes to be hereinafter described. Secured to the lower lift 11 by the fastening members 20 is the cup-shaped member 21 which is adapted to have a telescopic connection with the member 14. Projecting upwardly from the cup member 21 are tubular members 22 of a diameter less than the cylindrical members 18 to provide 65 for their reception therein. The tubular members 22 are provided with oppositely-disposed longitudinal slots 23 and disposed within said slots are the pins 19 carried by the cylindrical members 18. Mounted on 70 the upper ends of each of the tubular members 22 are the disk members 22', each of said disk members supporting a compression coil spring 24 disposed within the cylindrical members 18, engaging at its upper end 75 the plate 16 and at its lower end the disk members 22'.

The parts above described will be effectively guided in their several movements, but to insure such guiding movement, means 80 are provided as shown in Fig. 4, which consists of an angle plate 25 secured to one of the cylindrical members 18 as at 26 while its upper end is secured as at 27 to the plate 16. The lower end of the angle member 25 85 is provided with an opening in which is received a pin 28 carried by the lower cup-shaped member 21.

In operation, the member 14 and cylindrical members 18 are moved in a downward direction which compresses the spring 24 and permits the members 14 and 21 to telescope. When pressure is relieved on the upper lift 10, the spring 24 exerts itself and brings the telescoping sections to their normal position 95 as shown in Fig. 1.

While I have shown and described the preferred embodiment of my invention, I do not wish to confine myself thereto as various forms, modifications, and arrangements of the parts may be had without departing from the spirit and scope of the invention as claimed.

What is claimed as new is:—

1. A spring heel for shoes, comprising an upper and a lower lift, an inverted cup-shaped member depending from the upper lift, a cup-shaped member having its upper end fitting within said depending member, a plate within said depending member, cylin- 110

2

drical members depending from said plate, a cup-shaped member secured to the lower lift of the heel, vertically slotted tubular members projecting from the lower cup-shaped member, and telescopically engaging within said cylindrical members, disks on said tubular members, coil springs supported between said disks, and said plate, and pins extending within said cylindrical members, 10 and movable in the slots of said tubular members.

2. In a spring heel, the combination with two telescopically engaging sections, one having depending cylindrical members, and

the other provided with upwardly projecting tubular members, of vertically disposed coil-springs supported between the two members, and guiding means comprising an angle bracket secured to one of said telescopic members, and a vertically-disposed 15 guide pin secured to the other member and extending through an arm of said bracket.

In testimony whereof I affix my signature in presence of two witnesses.

FRANK KARÁCSONYI.
